UNITED STATES PATENT OFFICE.

JAMES N. SKINNER, OF NEW BRITAIN, CONNECTICUT.

LATHE-CHUCK.

SPECIFICATION forming part of Letters Patent No. 269,889, dated January 2, 1883.

Application filed September 14, 1882. (No model.)

To all whom it may concern:

Be it known that I, JAMES N. SKINNER, of New Britain, in the county of Hartford and State of Connecticut, have invented certain new and useful Improvements in Lathe-Chucks; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to what are known as "lathe-chucks," intended to hold a revolving tool for operating upon articles in a lathe—such as a drill—and also for holding any object which it is wished to revolve to be operated upon by stationary tools.

The object of my invention is to provide a small chuck which shall be simpler in its construction than the more complicated larger chucks, so that it can easily be made sufficiently small to hold the smallest tools or articles, and also to provide a simpler construction for the larger sizes for ordinary use.

In the accompanying drawings, illustrating my invention, Figure 1 shows a front view of my improved chuck. Fig. 2 shows a top view of the same. Fig. 3 is a longitudinal vertical section through the middle of the chuck. Fig. 4 is a rear view with the revolving back plate removed to show the interior construction.

A' A'' A''' are three parts or sectors, which, united form the circular face-plate and body of the chuck. These parts, when united, form a cylindrical body or stock, having a circular flange at its forward end for the face-plate. It is made in three parts, separated on radial lines for facility of construction, to permit the sockets and openings for the interior working parts to be more readily and easily cut in the metal.

B B B are the jaws. They project from the face-plate in the customary manner, and may be made of any of the usual forms to hold drills or other articles. As shown in the drawings, they are intended to hold a drill or round bar. The jaws are provided with projections B', 50 which move out or in radially in slots in the

face-plate, cut so as to lie one-half within the adjacent sectors forming the body of the chuck.

C C are screws for moving the jaws. They are furnished with bevel-gear wheels D, by which they are turned, as will be described. 55 One half of these screws and gears lie within the thickness of the face-plate, which is furnished with sockets to receive them. The sockets serve as bearings for the gear-wheel, so that the screws cannot move out or in radially, and the thread of the screw working in a hollow thread or nut in the projection B', the jaws are moved whenever the gears are revolved.

E is a ring lying just back of and close to 65 the face-plate and containing the other half of the sockets for the screws C and gears D. This ring lies close against the face-plate and is held in place by dowels or pins, so that it cannot turn upon it. It thus practically forms 70 part of the face-plate, but is made in a separate piece for convenience in cutting the sockets for the screws and their gears. It may be made as a simple ring provided with sockets for the cylindrical part of the shank of the 75 screws outside of the gears, so as to hold the screws in place, but is preferably made to fit upon the central body of the chuck.

F is a revolving annular plate, forming the back plate of the chuck. It is furnished with 80 a projecting ring, F', upon its face, which contains a circular beveled rack, gearing into the gear-wheels D. When this plate is revolved it turns the screws C and moves the jaws B out or in simultaneously.

G is a nut which screws upon the rear end of the body A of the chuck, formed by the three parts A', &c., before described. It rests against a shoulder at the lower end of the screw, so that when it is turned up tight it 90 holds all the parts of the chuck together; but is not so tight as to prevent the turning of the plate F.

H is a plug screwed into the hole which runs through the center of the body A, and fills its 95 rear end. Its purpose is to strengthen and support the body and hold the three parts of which it is composed in their exact position.

J is a continuation of the nut G to the rear, for the purpose of forming a connection with 100

the spindle of a lathe. It is provided with a socket, J', which is furnished with a hollow screw-thread fitting the screw on the lathe-spindle.

5 In order to adjust the jaws of my improved chuck so that they may be all equidistant from the center, or, if desired, to set them at any other position, I provide the outer ends of the spindles of the screws C with slots C', 10 by which they can be turned independently of each other. By loosening the nut G and drawing back the plate F, so that the circular rack becomes disengaged from the wheels D, either screw can be turned independently by means 15 of a screw-driver and the jaw set as far out or in as desired. The plate F is furnished around its outer rim with milling or a roughened surface, by which it is easily turned to set and clamp the jaws upon the article to be held. It 20 is also provided with holes for a spanner or

wrench to force it up tightly and give a firmer grip to the jaws when desired.

What I claim as my invention is—

1. In a lathe-chuck, the combination of the parts A' A'' A''', forming the body and face- 25 plate, the jaws B, the screws C, having the gear-wheels D, the ring E, the back plate having the circular rack F' and the nut G, substantially as described.

2. In a lathe-chuck, the body and face-plate 30 composed of the radial sectors A' A'' A''', substantially as described.

3. In a lathe-chuck, the combination of the three sectors A' A'' A''', forming the body and face-plate, with the nut G and the plug H, sub- 35 substantially as described.

JAMES N. SKINNER.
